CLAIM

The new, original, and ornamental design for a protective athletic glove, as shown and described.

DESCRIPTION

FIG. 1 is a top left elevational view of a protective athletic glove;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a top right elevational view thereof; and,

FIG. 8 is a bottom right elevational view thereof.

The broken lines in the drawings depict environmental subject matter only and form no part of the claimed design.
